UNITED STATES PATENT OFFICE.

HARRY G. HOFFMAN AND GEORGE C. EASTIN, OF MOUNT STERLING, KENTUCKY.

AUTOMATIC ALARM.

1,116,276.

Specification of Letters Patent. Patented Nov. 3, 1914.

Application filed September 9, 1913. Serial No. 788,897.

To all whom it may concern:

Be it known that we, HARRY G. HOFFMAN and GEORGE C. EASTIN, citizens of the United States, residing at Mount Sterling, in the county of Montgomery and State of Kentucky, have invented new and useful Improvements in Automatic Alarms, of which the following is a specification.

The invention relates to burglar alarms, and more particularly to the class of automatic alarms for traveling bags or the like.

The primary object of the invention is the provision of an alarm of this character wherein an audible signal will become active on the lifting of the bag; although the said alarm is especially designed for use in suit cases, trunks, jewelry boxes, or the like, thereby indicating to the owner or bystanders that the same is being tampered with or is in the possession of a wrong doer.

Another object of the invention is the provision of an alarm attachment of this character which can be readily and easily set so as to become active for the sounding of an audible signal on the lifting or carrying of the bag or other article to which the same is attached so as to indicate it is in the possession or hands of an intruder, the attachment being set in a novel manner so as to prevent a person other than the user of the bag gaining knowledge of whether or not the signal will be sounded on the lifting of the said article.

A further object of the invention is the provision of an alarm attachment of this character wherein the same can be readily applied to luggage, and which will automatically become active should the article be tampered with or in event an attempt is made to carry the same off from its place of rest by a person other than the rightful possessor.

A still further object of the invention is the provision of an alarm of this character which is extremely simple in construction, thoroughly reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a perspective view of a traveling bag with the alarm constructed in accordance with the invention

applied thereto. Fig. 2 is a vertical longitudinal sectional view through the same. Fig. 3 is a sectional view on the line 3—3 of Fig. 1. Fig. 4 is a sectional view on the line 4—4 of Fig. 1. Fig. 5 is a detail of the circuit closing plate.

Similar reference characters indicate corresponding parts throughout the several views in the drawing.

Referring to the drawing by numerals, 10 designates generally a traveling bag which is of any approved form and in which is mounted the alarm attachment presently described.

The bag 10 is provided as usual with the swinging top sections 11 and 12 respectively, which when closed can be readily locked together, one of the sections being designed to overlap the other, and the metallic frame 13 thereof carries a handle 14 and slideable latches 15 on opposite sides of the handle so that the top sections can be securely locked and the bag carried in the hand in the ordinary well-known manner.

The alarm attachment comprises a slideable circuit closing plate 16 which is suitably supported upon the frame 13 at the inner side of the cover section 11 and has connected thereto the stem or shank 17 of a hand knob 18, the stem being passed up through a suitable slot formed in the frame 13 and the cover section 11 so that the knob 18 will be projected exteriorly of the bag whereby on manipulating the knob the circuit closing plate 16 can be shifted for the opening or closing of an electric circuit comprising a battery 19, an electric bell 20, both of which being connected with the electric current wires 21, one of which is engaged with the hook end 22 carried at one extremity of an L-shaped hanger 13' loosely connected to one end of the handle 14 which has its other end loosely connected to a base plate 23 supporting the said handle, the plate 23 being suitably riveted or otherwise fixed to the frame 13 of the bag. The hanger 13' is slidably fitted as shown in any suitable bearing carried by the frame 13 exteriorly thereof. The other wire of the electric circuit is connected to the plate 16 at any suitable point thereof, the hook end 22 on the hanger 13' being adapted to work against one end of the plate 16 when moved in the path of the latter so that when the plate 16 and the end 22 contact the electric circuit will be closed for the sounding of

the bell 20, it being apparent that when the handle is raised the end 22 will be brought into contact with the plate 16 after the latter has been shifted into the path of movement of the said end 22 so that the circuit will be closed.

Interposed between the metal frame 13 of the section 11 and the hook-shaped end 22 of the handle 14 which projects interiorly 10 of the bag is a coiled expansion spring 24 which is designed to act upon the end 22 to normally hold it out of contact with the end of the plate 16 when the latter has been shifted to extend into the path of movement 15 thereof and the bag 10 is at rest so that the electric circuit will remain open until the bag is lifted from its resting place. The circuit closing plate 16 at its other end is formed with a curvature providing a laterally projected tongue 25 which is adapted 20 to extend into the path of movement of the depending lugs 26 on one of the latches 15, and when the bag is closed and locked this lug 26 will be out of contact with the tongue 25 on the plate, but should an attempt be 25 made to open the bag the lug 26 will be thrown against the tongue 25 so that the circuit will be closed through the latch 15 carrying the lug, the frame 13, the hanger 30 13', and contact 22, it being apparent that the wires 21 are connected with the contact 22 and with the plate 16, thus completing the circuit from the battery 19 through the bell 20 for the sounding of the latter. When 35 the plate 16 is shifted so that the other end thereof is out of the path of movement of the contact 22, the tongues 25 will also be shifted out of the path of the lug 26 on the latch 15 so that the sounding of the alarm is 40 obviated, the circuit in this instance remaining open to prevent the sounding of the bell 20. The plate 16 is suitably insulated from the metal frame 13, while the latch 15 is mounted directly on the latter so that the 45 circuit will be closed through the metal frame 13 when the latch 15 is moved to bring the lug 26 thereof in engagement with the tongue 25, it being understood of course that the plate 16 is shifted in a direction so as to 50 extend in the path of movement of the contact 22 to accomplish this.

Mounted on the section 11 in alinement with the knob 18 at intervals are false knobs 27 which are slidably fitted to the frame 13 55 and are designed to confuse a person when attempting to move the plate 16 to avoid the closing of the circuit for the sounding of the alarm. It is to be understood, however, that this plate 16 may be connected with any one 60 of the series of knobs 27, thereby assuring a particular combination known only to the user of the case for the setting of the alarm to assure the sounding thereof when the case is lifted or an attempt is being made to open the same by a wrong doer. The wiring

21, bell 20, and battery 19 are arranged between the lining and the body of the bag 10 so as to be concealed thereby, the bell being suitably shielded to avoid any interference with the sounding of the same when the 70 electric circuit is closed.

In the operation of the alarm, assuming that the bag 10 has been closed and locked and also the plate 16 has been shifted to the right of the bag 10 and the said bag is at 75 rest, should a person attempt to raise the bag by the handle 14 the hook end 22 thereof will contact with the end adjacent thereto of the plate 16, thereby closing the electric circuit and causing the sounding of the bell 80 20, thus signaling the owner or bystanders that an attempt is being made to carry the bag away by a wrong doer. Now, should an attempt be made to open the bag by moving the latch 15 the latter will bring its lug 85 26 into engagement with the contact end 25 of the plate 16, thus closing the electric circuit and causing the sounding of the bell as the circuit will be closed through the frame 13 to the said bell for the sounding thereof. 90

From the foregoing it is thought that the construction and manner of operation of the device will be clearly understood, and therefore a more extended explanation has been omitted.

95

What is claimed is:—

1. The combination with a receptacle, of an alarm comprising a normally open electric circuit having a bell, a circuit closing plate slidably fitted interiorly of the receptacle, and a handle movably supported on the receptacle and engageable with the plate for closing the electric circuit. 100

2. The combination with a receptacle, of an alarm comprising a normally open electric circuit having a bell, a circuit closing plate slidably fitted interiorly of the receptacle, a handle movably supported on the receptacle and engageable with the plate for closing the electric circuit, a latch on the receptacle for locking the same and movable into engagement with the plate for closing the electric circuit when the handle is out of contact with the said plate. 105

3. The combination with a receptacle, of an alarm comprising a normally open electric circuit having a bell, a circuit closing plate slidably fitted interiorly of the receptacle, a handle movably supported on the receptacle and engageable with the plate 120 for closing the electric circuit, a latch on the receptacle for locking the same and movable into engagement with the plate for closing the electric circuit when the handle is out of contact with the said plate, and means 125 for moving the plate into the path of movement of the handle or the latch.

4. The combination with a receptacle, of an alarm comprising a normally open electric circuit having a bell, a circuit clos- 130

ing plate slidably fitted interiorly of the receptacle, a handle movably supported on the receptacle and engageable with the plate for closing the electric circuit, a latch on the receptacle for locking the same and movable into engagement with the plate for closing the electric circuit when the handle is out of contact with the said plate, means for moving the plate into the path of movement of the handle or the latch, and false means

10

arranged exteriorly of the receptacle and simulative of the said first-named means.

In testimony whereof we affix our signatures in presence of two witnesses.

HARRY G. HOFFMAN.
GEORGE C. EASTIN.
